(57) **CLAIM**

The ornamental design for a digital camera display screen with transitional graphical user interface, as shown and described.

DESCRIPTION

FIG. 1 is a front, top and right side perspective view of a digital camera display screen with transitional graphical user interface showing our new design;

FIG. 2 is a front elevational view thereof;

FIG. 3 is a rear elevational view thereof showing a first image of the digital camera display screen with transitional graphical user interface;

FIG. 4 is a top plan view thereof;

FIG. 5 is a bottom plan view thereof;

FIG. 6 is a right side elevational view thereof;

FIG. 7 is a left side elevational view thereof;

FIG. 8 is a rear elevational view thereof showing a second transitional image of the digital camera display screen with transitional graphical user interface, transitioning from FIG. 3, constituting a first embodiment of the invention;

FIG. 9 is a rear elevational view thereof showing a second image of the digital camera display screen with transitional graphical user interface, transitioning from FIG. 3, constituting a second embodiment of the invention; and,

FIG. 10 is a rear elevational view thereof showing a second image of the digital camera display screen with transitional graphical user interface, transitioning from FIG. 3, constituting a third embodiment of the invention.

The process or period in which one image transitions to another image forms no part of the claimed design.

The broken line showing of the digital camera is for the purpose of illustrating environmental subject matter and forms no part of the claimed design.
